DUPLICATING MACHINE

John E. Euth, Chicago, Ill., assignor to United Autographic Register Co., Chicago, Ill., a corporation of Illinois

Application June 22, 1933, Serial No. 677,127

13 Claims. (Cl. 197—133)

This invention relates particularly to duplicating machines adapted to the purpose of filling in the forms of continuous-form stationery, and to improved means for manipulating the stationery 5 in the machine.

The primary object of the invention is to provide a simple, easily operable device for aligning stationery strips in writing position on the platen, and a tensioning device for drawing the stationery 10 taut in writing position. A further object of the invention is to provide an aligning and tensioning device which will permit a plurality of strips 15 of stationery to be threaded through the device simultaneously.

15 A further object of the invention is to provide an improved method for aligning and tensioning stationery wherein folds at the transverse lines 20 of weakening may be utilized to draw the strips into alignment and tension the same. In accordance with the present invention, register pins are provided on the frame of the machine, in advance of the flat platen, to engage register-perforations in continuous-form stationery led over the platen. A tensioning device is provided in 25 the rear of the platen which is in the form of a thin-edge blade adapted to form a sharp fold at the lines of weakening in the stationery, and then move rearwardly to exert a tension on the strips. The invention is illustrated in a preferred embodiment 30 in the accompanying drawings, in which—

Figure 1 is a side elevational view of a machine embodying the invention; Fig. 2, a broken plan view of the same, with the typewriter removed; Fig. 3, a broken longitudinal sectional view, taken as indicated at line 3 of Fig. 2; Fig. 4, an enlarged broken longitudinal sectional view, similar to Fig. 3, showing the tensioning device in released position; Fig. 5, a broken sectional view, 40 taken as indicated at line 5 of Fig. 2; Fig. 6, a sectional view of the guide-member, taken as indicated at line 6 of Fig. 2; Fig. 7, a broken side elevational view of the auxiliary frame of the tensioning device; Fig. 8, an enlarged elevational view showing one end of the auxiliary frame and slide in locked position; Fig. 9, an enlarged broken elevational view of the pitman and crank for 45 rocking the guide-member; Fig. 10, a vertical sectional view of the stationery roll and its supporting member; and Fig. 11, a broken sectional view of the depending hanger and shaft for supporting the roll.

In the embodiment illustrated, A designates a main frame comprising standards A', a surmounting bed A² in which is mounted a platen A³; B, a

typewriting machine movably mounted on the bed A²; C, a carbon-supply device carried by the bed of the machine; D, a clamping device operating in front of the platen A³; E, an aligning and tensioning device mounted between the arms of the bed A²; and F, multiple-strip stationery supported beneath the aligning and tensioning device E.

The frame A is of known construction having standards A' connected by cross-rods 10 which 10 are held by nuts 10^a. The bed A² is fixedly mounted on the standards and comprises arms connected at the rear by cross-rod 11, held by nuts 11^a, and at the front, with cross-bars 12.

Like the frame, the platen A³ is standard 15 equipment and is mounted in a manner usual to this type of machine. Such mounting is described in my co-pending application, Serial No. 391,207, filed September 9, 1929. The rear portion of the platen is held in raised position 20 by means of a system of levers supported on a front rock shaft 13 and a rear rock shaft 14. The front rock shaft is provided with a depending arm 13^a, and the rear rock shaft with an arm 14^a. The arms 13^a and 14^a are connected by 25 means of a tension spring 15. The rock shaft 14 is further provided with rigidly connected, forwardly extending arms 16 which engage the bifurcated end of bell cranks 17, of the clamping device D, which is journaled on the shaft 13. A 30 lever arm 18 is pivoted at 19, to the arm 16, and its front end bears against the lower side of the rock shaft 13. The rear portion of the lever arm 18 is connected to a rod 20 which may be drawn downwardly by means of a treadle 21 which is 35 pivoted at 22 to a fixed arm 23 on the cross-rod 10. The mechanism just described is ordinarily used to depress the writing platen, but for the purpose of the present invention, this action is not necessary, and it is used merely to raise the 40 clamping device D and actuate the aligning and tensioning device E, as will be explained below.

The typewriting machine B may be of any well known construction. It is capable of transverse movement in the operation of printing words, 45 characters, etc. and is movable longitudinally on the arms or rails which comprise the bed A².

The carbon-supply device C comprises a multiple-strip carbon-supply roll 24 and a take-up roll 25 mounted on opposite sides of the platen in 50 brackets 26, and is adapted to supply continuous-carbon strips across the platen.

The clamping device D comprises a tear-off bar 27 which is carried on the bell crank levers 17, and is provided with apertures 28 adapted to 55

slip over register pins 29, which may be fixedly mounted on the front cross-bar 12. A pair of paper guides 30 are also attached to the cross-bar 12 in front of the clamping member and help to 5 guide the stationery, while advancing the same over the platen.

The aligning and tensioning device E comprises an auxiliary frame 32 which is adapted to rest upon the rear cross-rod 11, and upon a pair 10 of studs 33 fastened to the bed A² in the rear of the platen.

As shown in Figs. 7-9, the side portions of the frame 32 comprise channel members 35 in which are mounted slide members 36. The slide members 15 are provided with slots 37 through which studs 38 project, from the channel member 35, to make a lost-motion connection between the two. Springs 39 are connected to the stud 38 and to the slide members at 40. These springs 20 urge the slide members rearwardly.

A guide-member 41 extends through slots 35^a in the channel members and is journaled in the slides 36. The end portions of the guide-member are equipped with cranks 42 which are held in 25 position by screws 43. As best shown in Figs. 5 and 6, the guide-member is of triangular cross-section so as to provide a sharp edge 41^a. To the lower side of the guide-member is fastened a pair of U-shaped guide fingers 44. The latter fingers 30 serve to direct the stationery properly as it is advanced from the source of supply around the guide-member to the platen.

The front ends of the channel members 35 are provided with L-shaped slots 45, and the front 35 ends of the slides 36 are provided with L-shaped slots 46. A cross-member 47 has trunnions 47^a which extend through the slots 45 and 46, and are connected to the cranks 42 by means of pitmans 48. The member 47 is urged rearwardly 40 by tension-springs 49 which are connected to the slides 36 by means of studs 50. By this arrangement, it will be seen that the springs 49 urge the cranks 42 rearwardly and tend to hold the guide-member in the position indicated by the dotted 45 lines in Fig. 7. The springs 49 may be somewhat stronger than the springs 39 so that when the cross-member 47 is drawn forwardly, the slides will also move forwardly until the rear ends of slots 37 reach the studs 38, and by continuing 50 to advance the member 47, the pitmans 48 will rock the guide member into the position shown in Fig. 4.

The cross-member 47 is actuated by means of a chain 50 which has one end adjustably connected to the frame 32 by means of a thumb screw 51. A crank-member 52 is pivotally mounted on the frame at 53, so that when its front end 52^a is depressed by the lever-arm 18, a roller 54 at its rear end will engage a loop in 60 the chain and thereby cause the cross-member to move twice as far as the roller 54.

The stationery F comprises a plurality of strips of slips 55, which are provided with register-perforations 56, and are connected end-to-end 65 at lines of weakening 57. The stationery may be zig-zag folded or in the form of a plural wound roll 58 as shown in Figs. 1 and 10. When a roll is used, the stationery is usually wound on a hollow cardboard core 59 whose ends are engaged 70 by sheet metal bushings 60. These bushings are impaled by a shaft 61, having a disc 62 adjustably held by a screw 62^a and a slidible disc 63 adapted to engage the bushings loosely and thereby form a slightly eccentric mounting for the roll 75 so that the roll will not spin while being un-

wound. The disc 63 may be removed by depressing a spring-pressed plunger 64 in the shaft. The shaft 61 is prevented from turning by having cut-out portions 61^a which engage slots 65 in supporting hangers 66 which are rigidly connected to the frame 32 by screws 66^a. 5

If it is desired to use zig-zag folded stationery, instead of a plural wound roll, a supply may be supported on a tray 67 (see Fig. 1). The tray has a cantilever mounting consisting of forwardly extending arms 68 which bear against the lower side of the lower cross-bar 10, and outwardly extending studs 69 which rest on the rear leg of the standards A'. 10

In order to assist in bending the stationery 15 around the guide-member 41, a presser-member 69, in the form of a bail, is pivotally connected to the frame 32 and normally rests on the paper. However, the guide-member is provided with a cam-arm 70 which serves to raise the presser-member slightly when the guide-member is rocked to the position shown in Fig. 4. 20

To load the machine, the cross-member 47 is drawn forwardly and depressed in the front end of the slots 45 and 46 so that the guide-member 25 41 is in the position shown in Fig. 4. The bail 69 may be swung rearwardly out of the way while loading the machine. The stationery strips are led back over the guide-member, slipped under the fingers 44, and led over the platen into 30 engagement with the register pins which are made accessible through the raising of the tear-off bar by depressing the foot treadle 21. When the treadle is released, the cross-member 47 will have been raised out of the vertical portions of 35 the slots and will slide rearwardly, causing the guide-member to rock into the position shown in Fig. 3, thereby causing a sharp bend in the strips at their lines of weakening. The guide-member is then permitted to slide rearwardly 40 further, under the influence of springs 39, and the edge 41^a will bring the folds of the strips into alignment and tension the stationery over the platen. After a set of forms has been filled in, the treadle is depressed, which action will 45 raise the tear-off bar and bring the aligning and tensioning device into the position shown in Fig. 4. The strips are then lifted from the pins and pulled out until the next set of perforations may 50 be slipped over the pins. Thereupon the treadle may be released and the new set of forms is aligned and tensioned while the completed set 55 may be severed on the tear-off bar.

It will be understood that the slides and pitmans may be provided with a series of openings 55 so as to be capable of adjustment to accommodate various lengths of forms.

The foregoing detailed description has been given for clearness of understanding only, and no unnecessary limitations should be understood 60 therefrom, but the appended claims should be construed as broadly as permissible, in view of the prior art.

I claim:

1. In a machine of the character set forth: a frame provided with a platen over which continuous-form stationery strips may be led; said strips being provided with transverse lines of weakening between forms; means in front of said platen for engaging the advance ends of said strips and limiting their rearward movement; and opposed tensioning means in rear of said platen adapted to engage folds formed in the strips at the lines of weakening and draw said strips taut over the platen. 70 75 75

2. Mechanism as specified in claim 1, in which the tensioning means is forwardly and rearwardly slidable in the frame.
3. Mechanism as specified in claim 1, in which 5 the tensioning means comprises a guide-member through which the strips are led, and said guide-member being capable of oscillation to form folds in said strips.
4. Mechanism as specified in claim 1, in which 10 the tensioning means comprises an oscillatable guide adapted to form the folds in said strips, and said guide is slidably mounted in the frame to align and tension said strips.
5. In a machine of the character set forth: 15 an aligning and tensioning device comprising an auxiliary frame adapted to be carried by the main frame of a machine; a pair of slides mounted in said auxiliary frame for forward and rearward movement therein; a slotted guide-member journaled in said slides; and means for actuating said slides and oscillating said guide-member.
6. Mechanism as set forth in claim 5, in which 20 lost-motion connections are provided between the slides and auxiliary frame and springs serve to urge said slides rearwardly in the frame, the guide-member is provided with cranks having pitmans and springs urging the pitmans rearwardly with respect to the slide, and a cross-member serves to connect the forward ends of 25 said pitmans, said springs being tensioned so that when the cross-member is moved forward, the guide-member will be moved forward prior to being oscillated.
7. In a machine of the character set forth, a 30 tensioning device comprising: a frame; forwardly and rearwardly shiftable slide-members mounted in said frame; a guide-member journaled in said slides and adapted to form a fold in a strip of stationery led thereover and draw the same rearwardly; a presser-member adapted to press the stationery into engagement with said guide-member; and means for releasing the engagement of the presser-member when the guide-member is oscillated.
- 45 8. In a machine of the character set forth, an aligning and tensioning device comprising: a frame having slides mounted so as to be forwardly and rearwardly shiftable therein; and a guide-member journaled in said slides, said guide-member comprising a bar having a thin edge and 50 equipped with guide-fingers adapted to confine a strip of stationery closely against said bar.
9. In a duplicating machine: a frame equipped 55 with a flat platen over which stationery strips provided with register-perforations may be led; register pins mounted on said frame in front of said platen; a spring-held clamping member mounted on said frame and adapted to grip stationery engaged by said pins; tensioning mechanism mounted in said frame in rear of the platen comprising an auxiliary frame equipped with slides in which a guide-member is journaled, lever-means for shifting and rocking said guide-member to form a fold in said strips and tension the same over the platen; and treadle mechanism mounted on the main frame and adapted to release said clamping member and actuate said lever-means.
10. Mechanism as specified in claim 9, in which the lever-means comprises a bell crank, one end 10 of which is engaged by the treadle mechanism and the other is equipped with a roller, said roller engaging a chain having one end adjustably connected to the auxiliary frame and the other end to a cross-member, and said cross-member engaging the slides and being linked to the guide-member so as to shift and rock the latter when drawn forward by said bell crank.
11. In a machine of the character set forth: 15 a frame equipped with a platen and with a stationery-clamping device in advance of the platen; an opposed movably mounted unit back of said platen comprising paper-bending and fold-engaging means; means tending to retract said unit; and manually operated means serving to 20 release said clamping device and paper-bending means and thereafter to reset said clamping device and bend the paper and urge the stationery rearwardly to align and tension the same over the platen.
12. In combination in a machine of the character set forth: a platen; stationery-holding device in front thereof adapted to engage and limit the rearward movement of a plurality of stationery strips led over said platen; and a retractable stationery bending and tensioning device 25 back of said platen, comprising a fold-engaging edge and associated means for forming a fold in the stationery.
13. The method of aligning and tensioning 30 continuous-form stationery equipped with uniformly spaced register-perforations and transverse lines of weakening between forms which comprises: engaging the register-perforations at the advance ends of the strips; and forming sharp 35 folds at a line of weakening in a succeeding portion of the stationery and exerting force at the folds to align and tension the strips.
